(57) CLAIM

The ornamental design for a case for grooming items, as shown and described.

DESCRIPTION

FIG. 1 is a left side, top, front perspective view of the case for grooming items showing our new design;

FIG. 2 is a front elevation view thereof;

FIG. 3 rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a right side, bottom, and rear perspective view thereof.

The dashed broken lines in the Figures show unclaimed portions of the case for grooming items.

1 Claim, 6 Drawing Sheets
